Inventor,

UNITED STATES PATENT OFFICE.

HENDRIK JAN JACOB JANSSEN, OF SCH. EDAM, NETHERLANDS.

ROTARY PUMP OR MOTOR.

1,370,317.

Specification of Letters Patent.

Patented Mar. 1, 1921.

Application filed October 20, 1919. Serial No. 331,992.

To all whom it may concern:

Be it known that I, HENDRIK JAN JACOB JANSSEN, engineer, a subject of the Queen of the Netherlands, residing at Schiedam, 5 the Netherlands, 203 A Warande, have invented certain new and useful Improvements in Rotary Pumps or Motors, of which the following is a specification.

The main objects of this invention are to 10 provide an improved form of rotary pump or motor; to provide an improved form and arrangement of the piston and rotor; and to provide improved means for supporting said piston so as to cause a relative reciprocation 15 between the rotor and piston during their rotation.

An illustrative embodiment of this invention is shown in the accompanying drawings, in which—

20 Figure 1 is a longitudinal section of the piston and supporting means.

Fig. 2 is a side elevation of the same.

Fig. 3 is a section taken on the line 3—3 of Fig. 1.

25 Fig. 4 is a longitudinal section of the pump or motor showing the parts in their assembled relation.

Fig. 5 is a section taken on the line 5—5 of Fig. 4.

30 As shown in the drawings, the improved form of pump or motor comprises a casing 5 in which there is concentrically arranged a rotor 7 and a piston 13 shiftably supported on said rotor and adapted to rotate therewith 35 about the eccentrically mounted shaft 9.

The casing 5 is cylindrical in form and is provided with inlet and outlet ports 1 and 2, located at diametrically opposite points. A cover member or plate 8 is bolted or otherwise 40 detachably secured to the casing to facilitate the assemblage and removal of the operating parts. A hub or bearing member 3 is formed on the plate 8 in eccentric relation to the rotor and casing and carries a bushing 4 for supporting the driving shaft 9.

The rotor 7 is of suitable shape to rotatably fit the walls of the casing and is provided with a passage 14 extending therethrough in which the piston is shiftably arranged 45 so that the chambers 14.1 at the ends of the piston between the walls of the casing and the rotor are expanded and contracted as they move into communication with the inlet and outlet ports 1 and 2 respectively. An opening 15 is formed in the walls

of the rotor so as to permit the free rotation of the rotor around the eccentric hub 3.

The piston 13 is supported on the inner end of the driving shaft and has a snug sliding fit with the passage 14. When the device 60 is used as a pump the shaft driven by a pulley 9.1, or other suitable means imparts a rotary movement to the piston and the rotor, and due to the eccentricity of the hub 3 with respect to the rotor and casing, the 65 rotation of the operating parts will cause a relative reciprocation of the piston and rotor in the direction of the longitudinal dimension of the piston. The length of the piston is less than the diameter of the rotor 70 so as to form the hereinbefore described chambers 14.1, and the eccentricity of the rotor and piston is such that during the rotation thereof the chambers 14.1 will be most fully expanded just after passing the inlet 75 port 1 and most fully contracted just before completely passing the outlet port 2.

The means for slidably supporting the piston on the driving shaft comprises a driving member 10 and a pair of links 11 and 12. 80 The member 10 is keyed to the driving shaft and is secured thereto by a set screw 16. Arms or parts 17 are formed on the member 10 and extend in opposite directions on diametrically opposite sides of the shaft 9. The 85 links are disposed in substantially parallel spaced relation and extend in opposite directions one on each side of the driving shaft. The inner ends of the links are pivoted to the member 10 by pins 18, and the 90 outer ends are pivoted to the piston by pins 19.

The operation of the device when used as a pump is substantially as follows:

The piston, which is driven by the eccentrically arranged power shafts 9, imparts a rotary movement to the rotor. As the piston approaches and passes the inlet port 1 moving in the direction of the arrow shown in Fig. 5, the lower end of the piston recedes 100 from the walls of the casing due to the eccentricity of the driving shaft and expands the chamber 14.1, so as to cause a suction of fluid in through the port 1. At the same time the chamber 14.1 at the other end is 105 being contracted so that the fluid is forced out through the outlet or discharge port 2.

Although but one specific embodiment of this invention has been herein shown and described, it will be understood that numer- 110

ous details of the construction shown may be altered or omitted without departing from the spirit of this invention as defined by the following claims.

5. I claim:

1. A device of the class described comprising a casing having inlet and outlet ports, a rotor arranged in said casing and having a radially disposed passage extending therethrough, a driving shaft rotatable in said casing on an axis eccentric to the axis of said rotor, a piston shiftably arranged in said passage and providing expansible and contractible chambers at the ends of said piston, said piston being rotatable with said rotor about the axis of said shaft, a driving member rigidly secured to said shaft, a link pivotally mounted on said piston, said link being pivotally connected to said member at a point removed from both of said eccentric axes, whereby said piston is caused to rotate about the axis of said shaft, and means for rotating said shaft so as to cause the rotation of said rotor and piston about their respective axes and the relative reciprocation of said piston on said rotor so as to expand and contract said chambers to cause an intake and discharge through said ports.
2. A device of the class described, comprising a casing having inlet and outlet ports, a rotor arranged in said casing and having a radially disposed passage extending therethrough, a driving shaft rotatable in said casing on an axis eccentric to the axis of said rotor, a piston shiftably arranged in said passage and providing expansible and contractible chambers at the ends of said piston, said piston being rotatable with said rotor about the axis of said shaft, a driving member rigidly secured to said shaft, a link pivotally mounted on said piston, said link being pivotally connected to said member at a point removed from the axis of rotation of said piston, the distance between said pivotal point of connection and the axis of rotation of said piston being greater than one-half the greatest depth of either of said chambers whereby said piston is caused to rotate about the axis of said shaft, and means for rotating said shaft so as to cause the rotation of said rotor and piston about their respective axes and the relative reciprocation of said piston on said rotor so as to expand and contract said chambers to cause an intake and discharge through said ports.
3. A device of the class described comprising

ing a casing having inlet and outlet ports, a rotor arranged in said casing and having a radially disposed passage extending therethrough, a driving shaft rotatable in said casing on an axis eccentric to the axis of said rotor, a piston shiftably arranged in said passage and providing expansible and contractible chambers at the ends of said piston, said piston being rotatable with said rotor about the axis of said shaft, a driving member rigidly secured to said shaft and having oppositely disposed arms, a pair of links extending in opposite directions and located on opposite sides of said shaft and having their inner ends pivotally connected to the respective arms of said driving member and their outer ends pivotally connected to said piston, and means for rotating said shaft so as to cause the rotation of said rotor and piston about their respective axes and the relative reciprocation of said piston on said rotor, so as to expand and contract said chambers to cause an intake and discharge through said ports.

4. A device of the class described, comprising a casing having inlet and outlet ports, a rotor arranged in said casing and having a radially disposed passage extending therethrough, a driving shaft rotatable in said casing on an axis eccentric to the axis of said rotor, a piston shiftably arranged in said passage and providing expansible and contractible chambers at the ends of said piston, said piston being rotatable with said rotor about the axis of said shaft, a driving member rigidly secured to said shaft and having oppositely disposed arms, a pair of links extending in opposite directions and located on opposite sides of said shaft and having their outer ends pivotally connected to said piston, the inner ends of said links being pivotally connected to the respective arms of said driving member at points removed from the axis of rotation of said piston, the distance between said last-mentioned pivotal points of connection and the axis of rotation of said piston being greater than one-half the greatest depth of either of said chambers, and means for rotating said shaft so as to cause the rotation of said rotor and piston about their respective axes and the relative reciprocation of said piston on said rotor so as to expand and contract said chambers to cause an intake and discharge through said ports.

In testimony whereof I affix my signature.

HENDRIK JAN JACOB JANSSEN.
